HUB CAP AND LOCK FOR THE SAME

Arthur Swartz, Detroit, Mich.

Application April 24, 1934, Serial No. 722,112

2 Claims. (Cl. 70—90)

My invention relates to hub caps and locks for the same and its principal object is to provide a hub cap for the wheels of automobiles and other vehicles which is compact in design, simple in construction, and which is, for the most part, made up from sheet steel stampings so that it may be produced quickly and economically by modern production methods.

Another object of my said invention is to provide a locking mechanism for the hub cap which, while utilizing a key-operated lock of the barrel or tumbler type, which is necessarily of small size and light construction, will at the same time be of strong and rugged construction as regards the parts which actually secure the hub cap in position.

A further object of my said invention is to provide a hub cap and lock for the same in which the delicate portions of the locking mechanism are effectually protected from dust and dirt and which at the same time are readily accessible to the operator.

With these and other objects in view, the invention consists in the improved construction, arrangement, and combination of parts which will be hereinafter fully described, reference being had to the accompanying drawing, which illustrates a preferred embodiment thereof, in which drawing—

Figure 1 is an elevation partly in section on line 1—1 of Figure 2, the outer cover being broken away to show one of the locking bolts.

Figure 2 is a section on line 2—2 of Figure 1.

Figure 3 is a fragmentary section on line 3—3 of Figure 2.

Figure 4 is a section on line 4—4 of Figure 3.

Figure 5 is a fragmentary plan view showing the latch means for securing the secondary cover in position.

Figure 6 is a fragmentary view similar to Fig. 2, with the central cover open.

Like characters designate corresponding parts throughout the several views.

1 is the hub cap, of such diameter as to abut upon the inturned part 2 which defines the opening in the body of the hub. Integral with the hub cap 1 is the housing 3 to which is secured, by spot-welding or other means, the base plate 4 which carries the main locking elements. In the center of and integral with the hub cap is the cylindrical projection 5 provided with a bore 6 adapted to receive the barrel 7 of a cylinder or tumbler lock of conventional type, the latter being provided with the usual flange 8 which abuts upon the upper face 9 of the projection

5. The hub cap is provided with an annular depression 10 adapted to receive the tightly fitted central cover 11 which serves to enclose the cylinder lock and to prevent access of dust and dirt thereto. Upon the rear face of the base 5 plate 4 are mounted the three radially disposed sliding bolts 12, the outer ends of which are guided in clips 13 pressed up from the material of the base plate itself, the said bolts being adapted to project beyond the periphery of the 10 housing 3 and engage the inner edge of the in-turned part 2 of the hub so as to retain the hub cap in place but which may, when desired, be withdrawn in a radial direction so that their ends are flush with the periphery of the housing 3. 15

The inner ends of the bolt 12 are provided with the oval portions 14, each of which has a central opening 15 on one side of which is a toothed rack 16, the latter being adapted to engage with the teeth of the pinion 17 mounted upon the inner 20 end of the rotatable cylinder 18 within the barrel 7 of the lock. In order to ensure simultaneous rotation of the cylinder 18 and the pinion 17, there is provided upon the end of the cylinder a square shaft 19 which projects through a correspondingly squared opening in the pinion and is provided at its outer end with a screw 20 and lock washer 21, there being a large washer 201 between the said lock washer and the pinion. It will be observed from the foregoing description and by reference to the drawing that rotation of the cylinder 18 by means of the usual key will cause the bolts 12 to be moved back and forth so as to lock or unlock the hub cap as desired. 35

In order to prevent undue friction between the ends of the pinion teeth and the inner surfaces of the openings 15, there is provided the vertical projection 22 which is formed from the material of the base plate 4, being pressed up 40 therefrom leaving openings 221 in the manner well known in the art. In order to retain the inner ends 14 of the bolts in position there is provided a disc 23, in the center of which is a circular opening in which is journaled the 45 rounded end of the shaft 19 which also preserves proper alignment of the said shaft. The disc 23 is provided with bent up extensions 230 terminating in feet 231 which are secured to the base plate 4 by spot-welding or other means. 50 The extensions 230 are so positioned as to act as stops to limit the inward movement of the bolts 12. In order to retain the cover 11 in place there is provided the arcuate tail piece 110 adapted to engage in a slot 24 in the hub 55

cap 1, and diametrically opposed to this tail piece is a slot 11 in the cover in which engages a triangular pawl 25 pivoted at 26 to the hub cap and normally maintained in the engaged position, as shown in Figure 2, by a coil spring 27 which is located within a slot in the pawl and maintained in position by the pivotal cotter pin 26. Within a recess 28 in the outer face of the hub cap 1 is located a button 29 having a reduced portion adapted to slide within a slot 30 and having its lower portion connected to one end of a flexible member 31, the other end of which is secured to the pawl 25 by spot-welding or other means, the arrangement being such that, by sliding the button 29 in a direction away from the center of the hub cap, the pawl 25 is retracted so as to release the cover 11 which can then be raised up so as to withdraw the tail piece 110 from the slot 24, thereby freeing the cover. In order to assist this movement there is the spring member 32, preferably formed from round wire, which normally presses against the underside of the cover 11, as shown in Figure 2, and is provided with rearward extensions 33 which terminate in outwardly bent hinged portions 34, these hinged portions passing through circular openings in the downwardly projecting edge of the cover. Beyond the hinged portions 34, and normally lying within recesses 112 in the rim of the cover 11, are the downward extensions 35 which terminate in horizontal members 36 extending in a direction away from the tail piece and terminating in hooked portions 37 which pass outwards through suitable openings in the hub cap and are bent into hooked form so as to be retained in position as shown in Figure 1. The shape of the spring member just described is so proportioned when in its free form that when the cover 11 is in the closed position shown in Figure 2 the portions 33 will be pressed downwards so as to provide a resilient upward pressure against the cover. Thus, when the pawl 25 is released as above described the cover 11 will be partially raised, after which it is manually withdrawn from the hub cap and then swung around upon the hinged portions 34 and the hooked portions 37 so that the flange 8 of the lock will be uncovered, but, at the same time, the cover will be still held in co-operative relation with the hub cap, loss of the cover thereby being prevented. In order to retain the barrel 7 of the lock in position and also to prevent rotation of the same, there is provided the resilient member 38 which is secured to the face 9 of the projection 5 upon the hub cap and is adapted to engage in a tangential slot in the barrel.

The button 29 is substantially oval in plan and

somewhat smaller in dimensions than the slot 30, the arrangement being such that when the parts are being assembled, the button 29 occupies a position at right angles to that shown in Figure 5 so that it may be passed through the slot 30, after which it is turned into the position shown and riveted securely in the proper position relative to the member 31. In order to facilitate final assembly of the last-named portions, there is provided the opening 39 in the base plate 4.

While I have herein described and shown a preferred embodiment of my invention, it will be readily understood by those skilled in the art that the same may be modified in various ways to meet any particular or peculiar requirement, without departing from the spirit of my invention.

Having thus described my said invention, what I claim and desire to secure by Letters Patent of the United States is:

1. The combination, with a lock having a barrel, of a casing for said lock having a back portion adapted to receive said barrel and an annular recess concentric with said barrel, a cover fitting within said recess and spaced apart from the face of said lock, means for retaining said cover in closed position, and hinge means for permanently securing said cover to said casing while permitting removal of said cover from said recess, said last named means comprising a slot in the peripheral wall of said recess, a latch in diametrically opposed relation to said slot, an arcuate tongue upon said cover adapted to engage said slot, a slot in said cover adapted to receive said latch, and a supplementary hinge member pivoted to said casing and to said cover at points spaced apart.

2. The combination, with a lock having a barrel, of a casing for said lock having a back portion adapted to receive said barrel and an annular recess concentric with said barrel, a cover fitting within said recess and spaced apart from the face of said lock, means for retaining said cover in closed position, and hinge means for permanently securing said cover to said casing while permitting removal of said cover from said recess, said last named means comprising a slot in the peripheral wall of said recess, a latch in diametrically opposed relation to said slot, an arcuate tongue upon said cover adapted to engage said slot, a slot in said cover adapted to receive said latch, and a supplementary hinge member pivoted to said casing and to said cover at points spaced apart, said last-mentioned member being adapted to resiliently press said cover in an outward direction.

ARTHUR SWARTZ.
